G. W. TAYLOR, JR

SIGNAL FOR TOY ELECTRIC TRAINS

Filed Nov. 8, 1926

UNITED STATES PATENT OFFICE.

GEORGE W. TAYLOR, JR., OF LEAVITTSBURG, OHIO.

SIGNAL FOR TOY ELECTRIC TRAINS.

Application filed November 8, 1926. Serial No. 146,998.

This invention relates to new and useful improvements in signals specifically adapted for use in conjunction with toy electrical railway systems and has for its primary object to provide a signal consisting generally of a vertical post upon the upper end of which is pivotally mounted a signal arm to be operated by an electro-magnet in open circuit with a storage battery or the house current, said circuit adapted to be completed to the magnet by reason of a toy train or car passing into an electrified block of the track unit.

A further and important object is to provide a signal of this character that is extremely simple of construction, inexpensive of manufacture, and one that is so constructed as to operate efficiently under all conditions.

Other objects and advantages of the invention will become apparent as the nature of the invention is better understood, the same comprising the novel form, combination, and arrangement of parts hereinafter more fully described, shown in the accompanying drawing and claimed.

In the drawing wherein like reference characters indicate corresponding parts throughout the several views:

Figure 1 is a perspective of the signal per se, and

Figure 2 is a diagrammatic view of the toy railway track unit and electrically connected to two electrified blocks of the trackway are a pair of the signals constructed in accordance with the present invention.

First having reference to the signal per se, 5 indicates a base block of any suitable material and design upon the center of which is arranged a vertically extending signal post 6, preferably of tapering formation and square shape in cross section. Within the upper end of this post 6 is a vertical slot 7 that opens at the opposite sides of the post, one end of the slot being of greater length than the other end as indicated by the full and dotted lines in Figure 1. Pivoted within this slot 7 as at 8 is a semaphore arm 9, the inner segmental plate portion 10 of which is provided with the usual circular and variously colored areas 11 which in the present instance may be provided by applying paint to the opposite sides of said segmental portion of the semaphore, or if desired holes may be placed

in said segmental portion and variously colored discs of material disposed therein.

Secured to the side of the post 6 beneath the segmental portion 10 of the semaphore arm and adjacent the lower end of the post is an electromagnet 12 that is secured to the post by a pair of straps 13-13 of metal or other equally as useful material.

Slidable vertically through the solenoid of the magnet 12 is a core 14 attached to the lower end of a pull wire 15 that extends upwardly and is connected at its upper end to the segmental portion of the semaphore arm outwardly of the post 6 as clearly indicated in Figure 1.

The electric wires from the magnet 12 extend through the lower end of the post 6 and thence beneath the base 5 in conventional manner after which the same are secured to binding posts 16-16 that terminate at the top side of the base block 5 and are provided with the usual wire binding screws 17-17.

In a diagrammatic view, Figure 2, there is disclosed a pair of signals as actually in use, and in this Figure A indicates the toy track way between the rails of which are arranged third rails B-B that are arranged around the ends and sides of the trackway, the ends of said rails being spaced apart as clearly indicated. Ordinarily, toy railway systems of this character are operated by the house current in which instance it is necessary to employ a transformer C. As usual, one binding post of the transformer is electrically connected to the outer rail of the track A, while the other binding post thereof is electrically connected to certain posts of the pair of signals, the other posts of the signals being respectively connected to the third rails B-B arranged around opposite ends and opposite sides of the track way. As soon as a car is disposed upon the track way, the circuit is completed to the magnet of one of the signals for operating the semaphore arm thereof. After the car moves out of one block it will pass to another block, thereby alternately operating the signals which are preferably disposed at opposite sides of the track way as indicated in the diagrammatic view, Figure 2.

It will therefore be seen that I have provided a highly novel, simple, and efficient toy signal for electric railways that is well adapted for all the purposes heretofore designated, and even though I have herein

2
shown and described the invention as consisting of certain detail structural elements it is nevertheless to be understood that some changes may be made therein without effecting the spirit and scope of the appended claim.

Having thus described my invention, what I claim as new and desire to secure by Letters Patent is:—

19. In a signal for toy electric railways, a base, a post extending upwardly from the base, said post being formed at its upper end with a transverse slot which extends through the opposite sides thereof, a semaphore arm extending through the slot and being pivoted therein, a segmental plate-
- 15

like portion formed on one end of the semaphore arm and having signalling means carried thereby, the slot on one side of the post being of a greater length than the slot 20 in the other side of the post, an electromagnetic solenoid secured on the side of the post through which the segmental plate like portion extends, a core operable vertically through the solenoid, means connecting the core to the segmental plate like portion of the semaphore arm, and a pair of binding posts arranged on the base and having electrical connection with said solenoid.

In testimony whereof I affix my signature.

GEORGE W. TAYLOR, JR.
